(57) **CLAIM**

The ornamental design for an anesthesia machine, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the file or records of the U.S. Patent and Trademark Office, but reserves all other copyright rights whatsoever.

FIG. 1 is a front perspective view of a first embodiment of an anesthesia machine, showing my new design;

FIG. 2 is another front perspective view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a top plan view thereof; and,

FIG. 8 is a top plan view of a second embodiment of an anesthesia machine that has an accessory arm capable of being transitioned between a retracted position and an extended position, wherein the accessory arm is shown in FIG. 8 in the retracted position, it being understood that the appearance of the second embodiment of an anesthesia machine is identical to that of the first embodiment of an anesthesia machine that is shown in FIGS. 1-7 when the accessory arm is in the extended position.

The broken lines immediately adjacent the shaded areas represent the bounds of the claimed design, while all other broken lines are directed to environment and are for illustrative purposes only; the broken lines form no part of the claimed design.
